UNITED STATES PATENT OFFICE.

WILLIAM L. STEVENS, OF MINNEAPOLIS, MINNESOTA.

MUSIC TURNER AND CARRIER.

1,397,885.

Specification of Letters Patent.

Patented Nov. 22, 1921.

Application filed January 31, 1920. Serial No. 355,306.

To all whom it may concern:

Be it known that I, WILLIAM L. STEVENS, a citizen of the United States, residing at Minneapolis, in the county of Hennepin and 5 State of Minnesota, have invented a new and useful Music Turner and Carrier, of which the following is a specification.

This invention relates to an improved music turner and carrier or folio, adapted 10 for containing music sheets, books or folders so that the same may be transported or carried from place to place, together with such additional music as it may be desired to play, and to turn the same successively in the 15 playing, reverse the same or return all of the sheets to an initial position so as to accommodate for repeats or replaying.

A further object of the invention is to provide a device of the character specified which 20 can be just as conveniently moved from one piano to another as a song book or folder, in addition to being a relatively desirable and perfect form of carrier or folio; which can be applied to a music stand as well as 25 to a piano, and which includes novel means for actuating a series of arms independently to turn the pages or sheets as the notes are played and each sheet is completed to permit said turning arms to be reversed at will and 30 to permit all of them to be turned back after the playing is completed, such mechanism being capable of convenient control by a hand or foot without inconveniencing the playing action and including a motor or ac- 35 tuating means of novel construction and simple in design, whereby the device is capable of being economically produced and sold.

With the above and other objects in view which will appear as the description pro- 40 ceeds, the invention resides in the combination and arrangement of parts and in the details of construction hereinafter described and claimed, it being understood that within the scope of what is claimed, changes in the 45 precise embodiment of the invention shown can be made without departing from the spirit of the invention.

In the accompanying drawings:

Figure 1 is a front elevation of my in- 50 proved music turner and carrier in an open position;

Fig. 2 is an enlarged vertical sectional

view taken on the line 2—2 of Fig. 1, but with the carrier or folio part omitted;

Fig. 3 is a detailed fragmentary perspective view of the operating chair and one of the turning arms, the same being shown in disassembled relation;

Fig. 4 is a side elevation of the device applied to a stand;

Fig. 5 is a plan view of the actuating means or motor;

Fig. 6 is a vertical sectional view thereof; and

Fig. 7 is a sectional elevation of the device 65 looking toward one side.

Referring to the drawings in detail, my improved music turner and carrier embodies a carrier proper 10 which is in the form of a folio or folder having the back portions 11 70 and 12 provided with the intermediate or binding portion 13 much in the same manner as an ordinary folio or book. The device is covered with leather, leather imitation or the like over stiff backings, which 75 backings are provided with coöperating handles 14 for convenience in transporting or carrying the device from place to place. A fastening strap 15 is also provided on one backing to engage its coöperating snap 80 fastener or socket member with a snap or ball member 16 carried by the other, although it is to be understood that any other suitable fastening means passing over the free edges and connecting the backings 85 may be employed. In this manner, the carrier or folio may be opened so as to rest upon the ledge of a piano music support or panel in convenient position for use.

Each of the backings is provided with a 90 suitable covering of leather or cloth at the inside as designated at 17 and each is formed with a pocket 18 between the inside lining and the outside cover or backings for accom- 95 modating additional music as clearly indicated in Fig. 1 of the drawings and without interfering with the ordinary use of the device. The operating mechanism for the device includes an elongated tubular housing 19 disposed vertically of the back- 100 ing 12 under the lining 17 and adjacent to the binding or intermediate part 13, said tube extending from the bottom to a point nearly at the top or slightly spaced from the

top edge of the folder and suitably secured in position. This tube rotatably receives a spindle 20, the upper end of which is of circular cross section and provided with a transverse key or pin 21 above the upper end of the tube or tubular casing. A series of turning arms 22 horizontally disposed are provided with leaf engaging clips 23 and said arms are provided at their inner ends with sleeves 24 having internal grooves or key slots 25 preferably terminating at spaced points from the upper and lower edges or ends thereof for receiving the pin or key 21 during the turning action, while the intermediate recesses 26 accommodate said pin between motions. The upper arm has its sleeve or hub in alinement therewith and the sleeves therebeneath are successively offset downwardly at different degrees or lengths as indicated at 27 so that the sleeves are accommodated on the projecting upper end of the spindle to turn freely thereon except when engaged by the key or pin 21.

At its intermediate portion, the spindle 20 is provided with a spiral groove or worm thread 28, the spindle being enlarged at this portion if desired and the tubular housing 19 having an opening 29 disposed through its wall axially of a latch casing 30 projecting from the housing. A latch or pin 31 is mounted in the casing and has a finger hold 32 by which it may be disengaged at its inner end from the groove, it being understood that said pin opposite its headed end engages the spiral groove 28, after passing through the opening 29. The pin is held in an engaged position in the manner of a spring pressed bolt or catch and for this purpose is provided with an enlargement 33 within the casing, between which and the outer end of the casing so as to encircle the pin, is disposed an expansible helical spring 34 so as to hold the pin normally in an engaged position by pressure against said enlargement or collar 33. By this means, the spindle may be caused to elevate as it turns or by withdrawing the pin, the spindle may be allowed to drop, so that the key 21 will be disposed in the grooves of the lowermost sleeve or hub 24 whereby the sleeves may be successively turned or swung to the left to turn the music sheets as the spindle is intermittently rotated and the means above described causes its elevation and successively brings the key into engagement with the grooves of the sleeves successively one above the other. It will be also understood as the key passes into the recesses, the sleeves will be released until the next groove is engaged to turn the succeeding arm as desired. When all of the arms have been turned and consequently the sheets, they may be turned back by means of an upright arm 35 carried by a

ring 36 from which it projects upwardly. 65 the ring having a finger piece 37 by which it may be turned in a groove in the housing 19. It will also be understood that the arms may be independently turned or swung backwardly for repeating or the like. 70

As shown particularly in Fig. 1 of the drawings, the upper portion of the housing, spindle and arms are exposed, the remaining portion being covered by the lining 17. The upper portion of the spindle is of 75 round or circular cross section as before stated, and the lower portion is of polygonal or square cross section as indicated at 38 so as to be connected to the actuating device or motor which includes a casing 39 in 80 which is rotatably mounted crown wheels or gears 40 mounted in vertical positions parallel to each other and provided with mutilated or spaced intermittent teeth and smooth portions 41. The lower end of the 85 shaft or spindle 20 is slidably engaged in a correspondingly formed opening in a beveled pinion or miter gear 42 disposed to mesh with the opposed inwardly extending teeth of the crown gears 40 which are 90 mounted to turn in the casing on stub shafts or pivots 43 which are fixed to the casing. Connecting the shafts or pivots 43 and the crown gears are spiral springs 44 like clock springs, the ends thereof being connected 95 to the pivots and to the gears respectively so as to operate the pinion 42 and the shaft 20 in opposite directions when connected thereto.

In order to wind the springs, the casing 100 is provided with a depending extension 45 in the front and rear walls of which is rotatably mounted a shaft 46 which is adapted to slide in and out so that the teeth of a pinion 47 fixed to the shaft may be disposed 105 in mesh with peripheral teeth 48 on the wheels or gears 40, which owing to their disposition at diametrically opposite sides of the pinion 42, serve to drive the latter in reverse directions. The shaft 46 is provided 110 with a key 49 and by pushing the shaft in, the pinion will engage the teeth 48 of the rear gear 40 so that the spring thereof may be wound. By pulling the shaft out through the medium of the key, the front gear spring 115 may be wound, and by disposing the pinion 47 at intermediate position, either gear 40 will be free to turn. In order to prevent said springs from unwinding, the gears are provided with ratchet extensions 50 at the 120 inside forming shoulders 51 facing in the direction in which the gears turn adapted to be engaged by a catch or pawl 52 passing through the casing at one side and pivoted intermediately of its ends on a vertical pivot 125 53 in a lateral extension 54 formed on or attached to the casing. At either side of the pivot, the pawl is provided with push

buttons 55 and 56 so that the pawl may be released from the position shown in Fig. 7 underlying the shoulders of both ratchet sleeves or extensions 50, wholly beneath one shoulder so that the other shoulder will be released in order that the corresponding gear may act under its spring to turn the pinions 42 and the spindle or shaft 20.

It will be seen that the shank portions of the buttons project through the lining 17 as well as the key 49 and in the operation of the device, the arms are disposed at the right hand side and engaged with the music sheets, except that the arm 35 will be disposed at the left. The spindle 20 will be in its lowermost position and with the springs properly wound and held from unwinding, the button 55 is depressed or repressed inwardly to rock the pawl 52 on its pivot 53 whereby the inner end of the pawl operating through the slot 57 in the casing at one side, will be disengaged from the shoulder 51 of the rear gear and into engagement with the shoulder of the front gear, thus holding the latter as before and releasing the former so as to turn the pinion 42 and the spindle in a clockwise direction or to swing the arms 22 successively to the left as released to correspondingly turn the sheets. By pressing the button 56, the pawl will be moved in the opposite direction to release the front gear and permit the other spring to act to return the arms to the right hand side, the rear gear being held against turning by engagement of the pawl beneath the corresponding shoulder 51, a series of which are provided corresponding to the spaced series of teeth on the gears 48. In this manner the arms may be independently returned for repeating, and it will also be seen that when the pinion 42 is disposed between smooth or mutilated portions of the gears or crown wheels 48, the spindle 20 may be freely turned by the upright arm 35 to return all of the arms and sheets to closed positions. The key 49 and the buttons 55 and 56 are conveniently located so as to be readily manipulated by the player and it will be seen that the buttons can be operated without interference to the playing.

In Fig. 4 of the drawings the device is shown applied to a music stand 58, preferably of the foldable type having the legs 59 and the rest 60 to the ledge of which is secured an arm 61 having pivoted thereto a plurality of bell crank levers 62, one for each button and connected by rods 63 to foot pedals 64 pivoted to the legs so that the buttons may be manipulated by the feet. Thus it will be seen that I have provided a simple and relatively inexpensive device for inclosing music folders or books and for supporting the same in position to be

turned and turning them as desired, whether applied to a piano or music stand adapted for use in playing string instruments, although it is to be understood that the device may be applied equally as well for turning sheets or pages other than music sheets, as for instance, for exhibition purposes or the like.

Having thus described the invention what I claim is:

1. In a music turner, a tubular spindle 75 housing, a shaft rotatable therein and provided with a worm thread, a releasable pin engaging the groove of said thread, a cross pin at the upper end of the spindle, a series of turning arms having hubs at different 80 elevations and provided with grooves for successive engagement by said pin as the spindle is elevated, said spindle when turned being elevated by said thread groove, a motor with which said spindle is operatively 85 connected and keyed for sliding movement to permit elevation thereof, means to impart intermittent rotation to the spindle in either direction, and means to return said arms after the same have been turned to one side. 90

2. A music turner and carrier comprising an elongated housing, a spindle mounted to turn therein, and projecting above the same, a cross pin carried by said projecting end, turning arms having sleeve portions engaged 95 on the spindle and provided with axial grooves and recesses above and below the same, said key being adapted to engage said grooves to turn the arms when the spindle is rotated with the key in engagement with 100 the grooves and operating freely thereof in the recesses, means for elevating the spindle upon rotation thereof in one direction and permitting the release thereof whereby it may be dropped to a lowered position, a folio 105 in which said parts are supported at one side of the binding, actuating means mounted at the lower end of the spindle to turn the latter in either direction, and repressible buttons for controlling said actuating means. 110

3. The combination with a carrier of a housing vertically mounted therein, a series of turning arms, a spindle rotatable in the housing and carrying said arms for intermittent turning in one direction, said arms 115 having leaf engaging means, spring means to return all of said arms to initial positions independently of the spindle, spring means for independently returning the arms and including a motor having a casing mounted 120 on the carrier at the lower end of the housing, oppositely acting and independently spring driven gears mounted in the casing, the lower end of the spindle being squared, a pinion slidably held thereon, means to 125 wind the springs of the gears, means to hold said gears against turning, and including a pawl and ratchet extensions on the gears en-

gageable by said pawl simultaneously or independently, and buttons for oppositely moving said pawl to hold both gears or to release either while holding the other to impart partial rotation to the spindle in either direction at will.

In testimony that I claim the foregoing as

my own, I have hereto affixed my signature in the presence of two witnesses.

WILLIAM L. STEVENS.
